CLAIM

The ornamental design for a gasoline driven cleaning machine, as shown.

DESCRIPTION

FIG. 1 is a front elevational view of a gasoline driven cleaning machine showing my new design;
 FIG. 2 is a rear elevational view thereof;
 FIG. 3 is a left side view thereof;
 FIG. 4 is a right side view thereof;
 FIG. 5 is a top plan view thereof; and,
 FIG. 6 is a bottom plan view thereof.
